UNITED STATES PATENT OFFICE.

JOHN HOUGHTON CLARKE, OF FRAMINGHAM, MASSACHUSETTS.

DEVELOPING-TRAY ROCKER.

SPECIFICATION forming part of Letters Patent No. 634,639, dated October 10, 1899.

Application filed May 16, 1896. Serial No. 591,746. (No model.)

To all whom it may concern:

Be it known that I, JOHN HOUGHTON CLARKE, of Framingham, in the county of Middlesex and State of Massachusetts, have invented a new and Improved Photodeveloping-Tray Rocker, of which the following is a full, clear, and exact description.

The object of the invention is to provide a new and improved photodeveloping-tray rocker, which is simple and durable in construction, designed to receive the ordinary developing-tray, and arranged to permit the operator to conveniently and easily impart the necessary motion to the tray to properly develop photographic plates contained in the tray and without requiring the operator to hold the tray in both hands.

The invention consists of a tray-rocker constructed as hereinafter described and claimed.

20 The invention also consists of certain parts and details and combinations of the same, as will be fully described hereinafter and then pointed out in the claims.

Reference is to be had to the accompanying drawings, forming a part of this specification, in which similar characters of reference indicate corresponding parts in all the views.

Figure 1 is a plan view of the tray-rocker. Fig. 2 is a sectional side elevation of the same on the line 2-2 of Fig. 1. Fig. 3 is a transverse section of the same on the line 3-3 of Fig. 1.

The improved tray-rocker is provided with a tray-receiving frame A, provided with a platform A', carrying at opposite sides the downwardly-extending rockers A'', adapted to rock on a table or other support, so as to impart a rocking motion to the platform A'.

In the platform A' is formed an opening A'', adapted to receive the tray containing the developer and the plates to be developed, and this tray B is formed with the usual inclined sides B', adapted to rest on the walls of the opening A'', so that the said tray B is firmly held in the platform A', and when the latter is rocked the tray rocks with it to cause the developer to gently pass over the film of the plate, so as to develop the negative in the proper manner.

50 It is understood that the operator by placing the finger on one end of the frame A can readily impart a rocking motion to the

said frame, so as to cause the developing liquid to pass over the plate quickly or slowly, according to the rocking motion given to the 55 frame. Thus the operator has the developing of the plate fully under his control and is not liable to soil or stain his fingers by contact with the developer, as is so frequently the case with trays of ordinary construction. 60

It will be seen by reference to Figs. 2 and 3 that the rockers A'' are of a suitable height to support the bottom of the tray B such a distance above the surface on which the frame is placed as to prevent the tray from touching the surface during the rocking operation. As illustrated in the said figures, the opening is of a size somewhat in excess of the size of the bottom of the tray, but less than the top surface of the tray, to cause the inclined 70 sides B' to snugly fit onto the walls of the opening A'' to support the tray in the frame. It will also be seen that by the arrangement described the operator can conveniently place the tray in position on the platform A' and 75 remove the same therefrom whenever the plates are developed.

It is further understood that the tray-rocker may be constructed for supporting two or more trays to permit of developing a number of 80 plates at the same time.

Having thus described my invention, I claim as new and desire to secure by Letters Patent—

1. As an improved article of manufacture 85 a jointless photodeveloping-tray rocker made from a single piece of material, the top of which has a cavity for the reception of the tray and the sides of which are parallel with each other and rounded or curved upon their 90 under edges.

2. A jointless photodeveloping-tray rocker made from a flat blank having a relatively large central tray-holding cavity the outer opposing edges of which blank are curved or 95 rounded and are bent or formed to become parallel with each other and to extend in the same direction from the remainder of the blank, as and for the purposes set forth.

JOHN HOUGHTON CLARKE.
